GEORGE H. ENNIS, OF LONG BEACH, CALIFORNIA, ASSIGNOR OF ONE-HALF TO ROBERT V. FUNK, OF LONG BEACH, CALIFORNIA

METHOD OF TESTING OPEN WELLS

Application filed February 3, 1930. Serial No. 425,521.

My invention relates to the testing of a well for determining the point at which water enters the well, and it further relates to an improved electrolyte for use in such tests.

In the drilling of an oil well it invariably occurs that water bearing strata are penetrated before the oil sands are reached. The water bearing strata must be sealed from the well; otherwise, the water will run thereinto, forming an emulsion, and in some instances reducing the oil yield of the well to the extent that the operation of the well is impractical.

According to present practice, the well is drilled and various casings are set in place. If it is found that water is leaking into the well, the point of leakage must be found and the water bearing strata must be sealed off. This sealing operation is usually accomplished by extending a casing down to a shale or rock stratum below the water bearing strata and cementing the casing thereto.

The last casing usually installed in a well is known as the oil string. The lower end of the oil string is extended into the oil sands and is perforated to allow the oil to enter. The upper end of the oil string is above the surface of the ground and is connected to piping for conveying away the oil. Sometimes water bearing strata are located adjacent the oil sands, and a portion of the perforated pipe passes therethrough, thus allowing the ingress of water into the well. When this condition exists, the water bearing strata must be found and cemented from the well.

The foregoing outlines the procedure of installing casing and cementing casing in a well when water leakages are encountered. There are processes at present for locating the leakage of water into the well after the casing strings have been set, and such a process is disclosed in my patent entitled Method and apparatus for determining the location of water strata in wells, No. 1,786,196, issued Dec. 23, 1930.

During the period of drilling and setting the casing, the well is kept full of rotary mud, which serves a number of purposes, such as holding the formations in place, preventing cave-ins and preventing premature flows of

oil. The rotary mud also holds back the seepage of water into the well, and because of this there will be no leakage of water into the well until after the casings have been set and the rotary mud removed from the well, so that the hydrostatic head is reduced sufficiently so that the pressure against the formations is insufficient to restrain an inward flow. At this time if there are any openings in or around the casing adjacent to or in communication with the water strata, the water will start to leak into the well. 55

It will therefore be seen that ordinarily the operator of the well has no way of knowing whether or not there will be water leakages into the well until after all the casings have been installed and the rotary mud removed from the well so that the hydrostatic head is reduced. Many thousands of dollars are sometimes spent in installing a casing in a well, and then when the rotary mud is removed, it is found that water still leaks into the well. 65

It is the purpose of my present invention to provide a method whereby the well may be tested for water leakages before all of the casings have been set and before the rotary mud has been removed, thus enabling the water leakages to be located and then sealed from the well by cementing or by the installation of the next casing. My invention further makes it possible to test a well for water leakages before any flow of oil has been started. 70

The preferred method of my invention includes the placing of an electrolyte in the well near the leakage point, if it can be estimated from the log of the well, or throughout the entire well if necessary, moving a pair of electrodes through the electrolyte, the electrodes cooperating with the surrounding portion of the electrolyte to provide a voltaic cell, and measuring the potential difference between the electrodes as they are moved through different positions in the well. As water seeps into the well, the electrolyte is weakened, which will change the potential difference between the electrodes and thus indicate to the operator whereat the leakage occurs. 85

In performing my method in an open hole 100

there may have been many difficulties to overcome and many problems to solve.

In an open hole, that is, in a well in which all the casing has not been set and in which a portion is unprotected by casing, the rotary mud is maintained in the hole for a number of reasons, as pointed out above. In order to test the well to locate the water strata, an electrolyte must be introduced into the well. This electrolyte which is to be used must possess all of the qualities of the rotary mud, such as pointed out heretofore, as well as its electrochemical qualities. It is further necessary that the electrolyte have qualities which prevent it from stratifying and prevent it from being driven into the formations by the hydrostatic head in the well.

My invention provides an electrolyte which has the essential qualities as specified above, which renders the method of testing in an open hole a success, by preserving the condition of the well during the testing.

I will now describe my invention in detail, and during the course of the following description reference will be had to the accompanying drawings in which:

Fig. 1 is a view illustrating a drilled well which is ready to be tested by my invention.

Fig. 2 is a view similar to Fig. 1 showing the testing apparatus in the well, which testing apparatus is of a type capable of performing my invention.

Fig. 3 is an enlarged sectional view showing a portion of the well with the electrolyte of my invention therein showing the manner in which the water leakage occurs to dilute the electrolyte.

Fig. 4 is a section through the electrode carrier used in performing my invention.

Fig. 5 is a section taken on the line 5—5 of Fig. 4.

Fig. 6 is a chart showing a series of tests actually made on a well of the Associated Oil Company in southern California.

Referring particularly to Fig. 1, the numeral 11 represents the well. According to customary methods well casings 12 and 13 are installed in the upper end of the well and cemented in place, as indicated at 14. The numerals 15 and 16 represent shale or rock formation. The numeral 17 represents a water bearing formation, and the numeral 18 represents the oil sand. Fig. 1 shows the well after drilling operations have ceased and before the final casing is set. The well at this time is filled with rotary mud 19 in order that the lower open portion 20 of the well will receive the necessary reinforcement to prevent cave-ins, and in order that there will be no flow of oil prior to the installation of the final casing and the necessary preparation at the surface of the well.

If any of the rotary mud is removed from the well at this time, the hydrostatic head

will be reduced, and the walls of the open hole may cave in. It is the usual practice to install the various casings in the well immediately after the drilling operations have been completed and to then remove the rotary mud from the well. If the subterranean pressure is sufficient to cause a natural flow of oil from the well, it is impossible thereafter to make a test for water leakages. On the other hand, if the subterranean pressure is insufficient to cause a natural flow, the condition of the well may be observed, and if the water is present, the well may then be tested to locate the place where the water leaks into the well and to seal the opening.

The first step in the process of my invention is performed when the well is in the condition shown in Fig. 1; that is to say, drilling operations have been completed and the well is full of rotary mud, as shown. The first step consists in introducing an electrolyte into the well. The electrolyte, which is indicated by the numeral 21 in Figs. 2 and 3, may be introduced at certain portions of the well so that the well may be tested by stages, or the entire well may be filled with this electrolyte.

The electrolyte which is used in the process must serve all of the purposes of rotary mud, such as holding the formation in place, preventing bridging, lubricating the walls of the well, preventing cave-ins, controlling the pressures, controlling the water, controlling the oil, controlling the gas, and holding angle formations in place; and in addition to this, the electrolyte must have its electrochemical characteristics and function as a part of a voltaic cell.

The electrolyte which I use includes a number of substances to endow it with the necessary characteristics.

For the electrochemical qualities I may use a solution of ammonium chloride, which is strongly ionizable, or an equivalent ionizable material which will retain its electrochemical qualities in the presence of the other substances which comprise a part of the electrolyte.

I may also use as an electrochemical material a solution which includes ammonium sulfate, sodium sulfate, and a colloidal material in a solution which is acid, with sulfuric acid and chromic acid. The colloidal material which I prefer to use is alcohol fermentation product of waste molasses after the removal of the alcohol therefrom. It is known technically as slop. This electrochemically active solution may be made as follows:

#1 Slop solution

- (A) Take 10 gallons of concentrated slop.
- (B) Take 5 gallons of water and add gradually $\frac{3}{4}$ gallon of sulfuric acid 66° Bé.
- (C) Mix A and B and bring to boil, heat for $\frac{1}{2}$ hour.

hour, let stand 12 hours. Siphon off 10 gallons.

#2 Ammonium sulfate solution

Dissolve 300# of ammonium sulfate (fertilizer grade 25% ammonia) in 60 gallons of cold water.

#3 Sodium bichromate solution

10 $3\frac{1}{2}$ parts (by weight) water, 3 parts (by weight) sodium bichromate, 1 part (by weight) 66° Bé. sulfuric acid.

Mixing

15 (A) Take 90 gallons ammonium sulfate solution #2, add to this 10 gallons of slop solution #1 which will make up 100 gallons of A solution. Make up 150 gallons of sodium bichromate or B solution. Mix 4 parts by volume of A solution and 6 parts of B solution, making 250 gallons of chemical solution to be distributed in fluid contents of well by patented dose distributor. The amount of solution used is 1 gallon of solution approximately to each 48 gallons of liquid in the well.

To endow the electrolyte with the necessary weight qualities which are essential to the electrolyte in order that it may support the walls of the hole and hold back the flow of oil, a heavy mineral in finely divided form is included in the electrolyte. As a weight material I prefer to use barium sulfate, BaSO_4 , and in some instances I add to the barium sulfate a glutinous or colloidal mineral, such as bentonite clay or other colloidal clays. The purpose of the bentonite clay, or the colloidal mineral, is to prevent the electrolyte from being driven by the hydrostatic head into the formation and to prevent stratification of the different substances which compose the electrolyte.

The proportions of the electrochemical material and the weight material, which is preferably barium sulfate, and the glutinous material, or colloidal mineral, which is preferably bentonite clay, is used in accordance with the requirements of the well. In some wells the formation is such that the specific gravity of the electrolyte may be lower than in other instances, and likewise in some wells it is desirable to use more or less colloidal mineral ingredients with the tendency of the electrolyte to penetrate the strata. In some instances the colloidal material may be eliminated, but I have found that the most satisfactory electrolyte is formed when at least a small percentage of colloidal mineral is used, due to the fact that the colloidal mineral acts as a suspender and prevents the different substances of the electrolyte from stratifying.

As an example of the proportions which I may use to form the electrolyte of my invention, I give the following formula. It

should be understood, however, that this formula is illustrative only, and I do not intend to limit myself to the proportions stated.

	Per cent
Electrochemical material	85
Glutinous material	10
Weight material	5

The electrolyte may be introduced into the well in various manners. One way of introducing the electrolyte is to use the distributor disclosed in my patent for dose distributor, No. 1,725,979, patented August 27, 1929.

Another method of introducing the electrolyte is to extend into the well 11 a pipe or tube 25 which is connected to a pump 26 which draws the electrolyte from a source of supply. The electrolyte is pumped through the pipe 25 into the well, the lower end of the pipe extending to the lower end of the well or to a point where the electrolyte is to be introduced. By this means the entire well or a portion of the well may be filled with electrolyte. If desired, it is practical to test the well in sections, filling different portions of the well with electrolyte, so that it is not necessary to use a large amount of the electrolyte. In Fig. 2 the electrolyte 21 is shown as placed between the lower and upper bodies of rotary mud 30 and 31 respectively. It is sometimes possible to locate the ingress of water by the use of a charge of electrolyte which is properly placed according to indications given to the driller during the drilling operation.

In the step of introducing the electrolyte into the well it is absolutely essential to maintain a hydrostatic head which is sufficient to prevent cave-ins and to prevent a premature flow of oil. The two methods outlined are satisfactory ones for introducing the electrolyte.

The next step in the process is to make a test of the well to determine the uniformity of the electrolyte which has been introduced. This is accomplished by using the testing device shown in Figs. 2, 4, and 5.

The testing device consists of a frame 32 having a guide means 33 at the lower end thereof and having a cable 34 attached to the upper end thereof. Supported in the shell 32 is an insulation block 35 having a central opening 36, which insulation block 35 supports a pair of relatively spaced electrodes 37 and 38. The electrodes 37 and 38 must be made of such material as will cooperate with the electrolyte to form a voltaic cell. It is well known in the art what metals may be used for this purpose. In my device, I find it commercially practical to use electropositive electrodes made from aluminum, chromium, manganese, zinc, iron, cobalt, and electronegative electrodes made from nickel, lead, cadmium, tin, copper, silver, antimony, or gold.

Connected to the electrodes 37 and 38 are electrical conductors 40 and 41 which may be extended to the surface of the ground through the cable 34. The cable 34 extends over a guide sheave 42 and may be wound on a suitable drum 43. The conductors 40 and 41 are joined to rings 44 and 45 which are engaged by brushes 46 and 47 respectively. The brushes are included in conductors 49 which are joined to a millivoltmeter 50. The testing device, which will be generally indicated by the numeral 51, is lowered by means of the cable 34 through the electrolyte 21. When passing through the electrolyte 21, the millivoltmeter 50 should give a constant reading and usually gives a reading of about 200 points which is about 10 millivolts. If it is found that the electrolyte is uniform, the next step in the process is conducted. If a non-uniform reading is obtained, a redistribution of the electrolyte must be performed.

The next step in the process is to cause the flow of fluid into the well from the surrounding formation. This is preferably accomplished by reducing the hydrostatic head in the well. A bailer may be extended into the upper end of the well, and a relatively small amount of the rotary mud or of the electrolyte removed from the top of the well. When the hydrostatic head is thus reduced, the pressure of the electrolyte tending to hold the fluid in the formation is reduced and will permit an inflow into the well. As shown best in Fig. 3, the electrolyte adjacent to the water bearing formation will be diluted or weakened, as indicated at 60, by the inflow of water.

The testing apparatus is again moved through the electrolyte in the manner just described. Where the electrolyte is undiluted, the reading will be the same as prior to the step just described of causing fluid to flow into the well from the surrounding formation. Where the fluid has flowed into the well, however, the strength of the electrolyte will be reduced and the millivoltmeter will show a lower reading. Another way of expressing the same function is that when the two electrodes 37 and 38 are in the unadulterated electrolyte, the potential difference will remain constant. When the electrodes move to that portion of the electrolyte which has been diluted and where the electrochemical action has been reduced, the potential difference between the electrodes will be reduced in a certain proportion.

It is usually desirable to retest a well two or three times by performing the two preceding steps. In other words, the hydrostatic head is reduced to permit the flow of fluid into the well, and the test is made; then the hydrostatic head is again reduced to cause a flow of additional water into the well.

In Fig. 6, the test chart shows four tests which were made on a well. Test No. 1

was made before the hydrostatic head had been reduced. Test No. 2 was made after the hydrostatic head had been reduced once. Test No. 3 was made after the hydrostatic head had been reduced twice, and Test No. 4 was made after the hydrostatic head had been reduced a third time. At the upper end of the separate readings, the numerals 20, 40, 60, etc. to 200, represent calibrations on the millivoltmeters. The cross-hatched portions of the chart represent the reading given by the millivoltmeters at the various depths indicated on the left side of Fig. 6. In Test No. 2 it is shown that the electrolyte was diluted at a depth of 8250 to 8270 feet. Test No. 3 shows that the electrolyte at 8260 to 8270 feet was diluted the most. As more water had entered the well, however, the water spread slightly so that the dilution of the electrolyte commenced at 8190 feet. In Test No. 4, a complete bridging of the water occurred at 8270 feet. The dilution of the electrolyte extended up to 8040 feet. The chart shown in Fig. 6 has been made from readings taken during the test of a well in southern California.

The step just described in connection with Fig. 6 completes the method of my invention. The location of the water entry has been found, and, as indicated by the chart referred to, the water in that particular well entered at a level of 8250 to 8270 feet. The next activity in the well is to seal the water bearing stratum from the well. This may be done by extending a casing downward to the shale or rock stratum, such as 16, located below the water bearing formation 17. The casing is then cemented in place, which completely seals the water from the well. In some cases the leakage may be arrested by forming a cement plug in the well and then drilling through it.

The operator will then install the oil string and prepare the equipment at the surface of the ground for accommodating the oil. The rotary mud is then removed. If the well is a flowing well, the oil will commence to flow. If not, pumping apparatus must be installed and the oil pumped to the surface of the ground.

My invention is not limited to use in open holes but may be used after all casing has been set and either before or after the rotary mud has been removed.

I claim as my invention:

1. A method of testing a well to find water leakages, prior to the removal of rotary mud from the well, said method comprising: placing a body of electrolyte in said well between layers of rotary mud; bailing rotary mud from the upper end of the well to allow an ingress of water; and electrochemically testing said electrolyte to determine whether or not it has been diluted.

2. A method of testing a well to find water

leakages, prior to the removal of rotary mud from the well, said method comprising: incorporating a weight material in an electrolyte; placing a body of said electrolyte in said well between layers of rotary mud; bailing rotary mud from the upper end of the well to allow an ingress of water; and electrochemically testing said electrolyte to determine whether or not it has been diluted.

10 3. A method of testing a well to find water leakages, prior to the removal of rotary mud from the well, said method comprising: incorporating barium sulphate, BaSO_4 , in an electrolyte; placing a body of said electrolyte in said well between layers of rotary mud; bailing rotary mud from the upper end of the well to allow an ingress of water; and electrochemically testing said electrolyte to determine whether or not it has been diluted.

15 4. A method of testing a well to find water leakages, prior to the removal of rotary mud from the well, said method comprising: incorporating a weight material and a glutinous material in an electrolyte placing a body 25 of said electrolyte in said well between layers of rotary mud; bailing rotary mud from the upper end of the well to allow an ingress of water; and electrochemically testing said electrolyte to determine whether or not it has been diluted.

20 5. A method of testing a well to find water leakages, prior to the removal of rotary mud from the well, said method comprising: incorporating a weight material and a colloidal clay in an electrolyte; placing a body of said electrolyte in said well between layers of rotary mud; bailing rotary mud from the upper end of the well to allow an ingress of water; and electrochemically testing said 40 electrolyte to determine whether or not it has been diluted.

6. A method of testing a well to find water leakages, prior to the removal of rotary mud from the well, said method comprising: 45 forming an electrolyte of substantially the same density as said rotary mud, placing a body of said electrolyte in said well between layers of said rotary mud; bailing rotary mud from the upper end of the well to allow 50 an ingress of water; and electrochemically testing said electrolyte to determine whether or not it has been diluted.

7. A method of testing a well to find water leakages, prior to the removal of rotary mud 55 from the well, said method comprising: forming an electrolyte of substantially the same viscosity as rotary mud; placing a body of said electrolyte in said well between layers of rotary mud; bailing rotary mud from the 60 upper end of the well to allow an ingress of water; and electrochemically testing said electrolyte to determine whether or not it has been diluted.

8. A method of testing a well to find water 65 leakages, prior to the removal of rotary mud

from the well, said method comprising: forming an electrolyte of substantially the same glutinous characteristics as said rotary mud; placing a body of said electrolyte in said well between layers of rotary mud; bailing rotary mud from the upper end of the well to allow an ingress of water; and electrochemically testing said electrolyte to determine whether or not it has been diluted.

70 9. A method of testing a well filled with a 75 liquid, said method comprising: incorporating a weight material in an electrolyte to make it of substantially the same specific gravity as said liquid; placing said electrolyte in said well between two layers of liquid; bailing said liquid from said well, and electrochemically testing said electrolyte.

In testimony whereof, I have hereunto set my hand at Los Angeles, California, this 28th day of January, 1930.

80 85 GEORGE H. ENNIS.
